UNITED STATES PATENT OFFICE

ROBERT W. COE AND MILLER M. BACON, OF TAMPA, FLORIDA

RAILWAY-CAR-RUNWAY CONSTRUCTION

Application filed January 12, 1929. Serial No. 332,117.

The present invention relates to runways such as are used on top of freight cars and the prime object of the invention resides in the provision of a structure of this nature 5 wherein the parts may be easily and quickly assembled and disassembled thereby allowing repair to be accomplished in an economical manner.

Another very important object of the invention resides in the provision of a runway of this nature which is simple in its construction, strong and durable, inexpensive to manufacture, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of a freight car with our runway thereon showing parts in 25 section,

Figure 2 is a side elevation thereof,

Figure 3 is an end elevation thereof,

Figure 4 is a fragmentary enlarged longitudinal section taken substantially on the line 30 4—4 of Figure 1,

Figure 5 is an enlarged detail transverse section taken substantially on the line 5—5 of Figure 1,

Figure 6 is an enlarged detail transverse section taken substantially on the line 6—6 of Figure 1,

Figure 7 is a perspective view of one of the cap plates,

Figure 8 is a fragmentary perspective view 40 showing the center of one of the boards,

Figure 9 is a perspective view of one of the brackets, and

Figure 10 is a fragmentary perspective showing one end of one of the boards.

Referring to the drawing in detail it will be seen that the numeral 5 denotes the roof of a freight car which has arranged transversely thereon a plurality of running board supporting brackets A and B. The brackets 50 A are adapted to support the ends of the

boards while the brackets B support the intermediaries thereof.

Each bracket A comprises an elongated top plate 6 with depending end legs 7 merging into outwardly directed spaced ears 8. 55 Spaced ears 8 are secured to the roof 5 by suitable fastening elements 9. The upper surface of the plate 6 is formed with pockets 10 to receive the ends 11 of running boards 12, said ends 11 being reduced so that cap plates 60 C may be fastened thereover flush with the boards.

These cap plates C include elongated top plates 14 with depending legs 15 fastened to the legs 7 by suitable fastening elements 16. 65 Each bracket B comprises an elongated top plate 17 with depending end legs 18 merging into outwardly directed base ears 19 secured to the roof 5 by suitable fastening elements 20. Cap plates C' are identical with cap plates C and hold the boards on the brackets B and the centers of the boards are recessed as is indicated at 21 so that the cap plates C' will be flush with the boards.

Fastening elements 16' secure the cap 75 plates C' to the brackets B.

Special end brackets D support the outer ends of the end running board. Each bracket D includes a horizontal plate portion 25 merging into a downwardly and sidewardly 80 inclined plate portion 26. The extremity of the plate portion 25 merges into a leg 27 depending therefrom and this leg in turn merges into an outwardly directed base ear 28 fastened as at 29 to the roof 5. 85

The extension or inclined plate 26 merges into a leg 30 which is suitably fixed to the side of the car. The plate 25 is formed with an extension 31 to overlap the reduced ends 11 of the boards 12 supported thereby. A 90 special bracket E is disposed alongside of the plate portion 26 in spaced parallelism thereto and has an overlapping extension 34.

The plate 26 has an overlapping extension 35 so that comparatively short strips or 95 boards 36, extending across the plate 26 and the brackets and having reduced ends to fit under the overlapping extensions 34 and 35 may be mounted in place. Cross brackets 37 are disposed between the plate portion 26 and the 100

bracket and handles 38 are secured thereto.

Elements 16 and 16' are preferably in the form of elongated bolts having heads 39 at one end and cotter pins 40 at the other end. 5 Obviously by removing the cotter pins, the bolts may be removed and cap plates removed so that the boards may be easily and quickly replaced.

It will further be seen that the structure is 10 decidedly simple, inexpensive to manufacture and strong and durable. The present embodiment of the invention has been disclosed in considerable detail merely for the purposes of exemplification, since in actual practice it 15 attains the features of advantage enumerated as desirable in the statement of the invention and the above description.

It will be apparent that changes in the details of construction, and in the combination 20 and arrangement of parts may be resorted to without departing from the spirit or scope of the invention as hereinafter claimed or sacrificing any of its advantages.

Having thus described our invention, what 25 we claim as new is:

1. In combination with the roof of a freight car, a plurality of intermediate brackets mounted crosswise thereon in spaced relation, longitudinal strips mounted on the intermediate brackets, end brackets of greater length than the intermediate brackets each extending to one of the longitudinal sides of the roof and adapted to support one end of the strips, comparatively short strips mounted on the extended portion of the end brackets, supporting legs on the end brackets, a lateral extension thereon having an upwardly and rearwardly turned channel-forming marginal portion for the reception of the strip ends, 40 and an upwardly and inwardly directed retaining tongue on one end of the end brackets for engagement with the upper faces of the comparatively short strips.

2. In combination with the roof of a freight car, a plurality of intermediate brackets mounted crosswise thereon in spaced relation to the longitudinal sides thereof, longitudinal strips mounted on the intermediate brackets, and a pair of end brackets of greater length 50 than the intermediate brackets having inclined portions extending to the longitudinal sides of the car, comparatively short strips supported on the inclined portions, channel-forming flanges on one of the end brackets for the reception of the ends of the first named strips, and integral inwardly turned elongated tongues extending over the inclined portions for retaining the short strips thereon.

3. In combination with the roof of a freight car, a plurality of intermediate brackets mounted crosswise thereon in spaced relation, longitudinal strips mounted on the brackets, pairs of spaced brackets of greater length 55 than the intermediate brackets extending to

the longitudinal sides of the roof and having horizontal and inclined portions and adapted to support the strips on the horizontal portions thereof, a lateral extension on one of each pair of the second named brackets terminating in an inwardly turned channel forming flange for the reception of the strip ends for retaining same on the bracket, comparatively short strips mounted on the inclined portions of the second named brackets, integral supporting legs on the opposite ends of the second named brackets, and elongated retaining tongues integrally formed on one end of the second named brackets and extending over the inclined portions thereof for retaining the short strips thereon.

In testimony whereof we affix our signatures.

ROBERT W. COE.
MILER M. BACON.
